UNITED STATES PATENT OFFICE.

ALBERT E. SHEILL, OF BIRMINGHAM, MICHIGAN, ASSIGNOR TO WITCHELL SHEILL CO., OF DETROIT, MICHIGAN, A CORPORATION OF MICHIGAN.

SPORT SHOE.

Application filed November 28, 1927. Serial No. 236,027.

This invention relates to shoes for athletes or others following the various sports and which shoes are designed to prevent the person wearing them from slipping on the surface over which they are traveling. Such shoes are usually provided with projecting studs or what is known as cleats secured to the sole and heel portions of the shoe. It is common practice to make these cleats detachable so that they may be renewed when broken or worn and the object of the present invention is to provide an attachment which is such as to preclude the possibility of the fastening device being broken under the heavy strain to which these cleats are subjected when in use. A further object is to so construct each cleat and its fastening device as to facilitate the removal and replacement of the cleat and also to prevent the body of the cleat from being broken away and exposing its fastening means, leaving the fastening means in such a condition as to cause injury to the other players by reason of the exposed metal fastener being left projecting from the shoe sole without being covered by the cleat. It is also an object to provide a strong and rigid metal core for the cleat upon which core the cleat is molded and very securely attached thereto by the intimate engagement of the cleat body therewith. A further object of the present invention is to provide a cleat fastener so arranged as to firmly and securely clamp the same in place on the shoe sole and after being clamped is securely locked against detachment, said fastening means including a screw stud and a reinforcing member arranged to receive and hold the cleat and at the same time strengthen the screw stud.

With the above and other ends in view, the invention consists in the matters hereinafter set forth and more particularly pointed out in the appended claims reference being had to the accompanying drawing in which

Figure 1 is an inverted plan view of a shoe showing cleats applied to the sole and heel portions thereof, with some of these cleats which embody the present invention shown in section and with portions removed to more clearly disclose the construction;

Fig. 2 is an enlarged longitudinal section substantially upon the line 2—2 of Fig. 1;

Fig. 3 is a further enlarged sectional view of the cleat and its attaching means;

Fig. 4 is a sectional view similar to that of Fig. 2 and illustrating a modified construction;

Fig. 5 is a plan view of a metal sole plate;

Fig. 6 is a sectional detail illustrating the manner of attaching screw studs to the metal sole plate, and

Fig. 7 is an enlarged inverted end elevation of the screw stud shown in Fig. 6.

The shoe shown in the accompanying drawing is merely illustrative of a form of shoe to which the cleats embodying the present invention may be attached, this shoe being of any well known construction and having an outsole 1 and insole 2 and a heel 3. As these cleats may be applied to either the sole or heel or both, and applied in the same manner to each part, their application to the shoe is illustrated in detail by showing the same in the details as applied to the sole of the shoe.

Referring more particularly to Figs. 2 and 3, the cleats 4 are preferably formed from hard rubber or other material which may be molded or cast into the desired form, the body of the cleat being preferably of truncated conical formation and embedded within each cleat body is a metal core 5 in the form of a thimble or tubular member having a closed inner end and provided with external annular grooves 6 so that when this core or thimble is set within the mold in which the cleat body is formed, the material of the body will flow into the grooves 6 and be firmly united with the core to preclude the possibility of the cleat body from being split or turned away from the thimble in use.

To securely and detachably attach each cleat to the sole of the shoe, the screw-threaded stud 7 is provided and this stud is forced through an opening in the inner and outer soles of the shoe with a flat head 8 on the stud embedded within the inner sole 2. Ribs 9 on the stud beneath its head 8 are provided for the purpose of prevent-

ing the rotation of the stud after it has been forced through the sole with its head and the ribs 9 firmly embedded in the shoe sole. The stud 7 is further securely held in place 5 by a clamping and reinforcing member 10 which comprises an internally and externally screwthreaded sleeve 11 having a base flange 12 and an opening 13 in this flange. This 10 and an opening 13 in this flange. This 12 and an opening 13 in this flange. This 15 clamping member 10 is screwed upon the stud 7 after the stud has been passed through the shoe sole and is turned down hard against the outer surface of the sole with its flange 12 in firm contact therewith. The 20 stud is therefore firmly clamped in place and the sole compressed between the head 8 of the stud and the flange 12 of the clamping member. After the stud has been so secured in place by the clamping member 10, said member is firmly and securely locked against 25 rotation upon the stud 7, by means of a nail or other fastening member 14 which is driven into the sole through the opening 13 in the flange of the locking member 10.

The core or thimble 5 is internally screw-threaded to receive the externally screw-threaded sleeve of the clamping member 10 and the base of the cleat 4 is recessed as at 15 to receive the flange 12 of the clamping member when the cleat is screwed into place 20 upon said sleeve of said clamping member, and therefore the annular edge portion of the base of the cleat will come into firm engagement with the surface of the shoe sole 25 outside of the flange 12 and have a firm bearing thereon to prevent any lateral movement under strain when the shoe is in use.

By providing the clamping member with a sleeve portion to screw upon the stud 7, this clamping member not only holds the 40 screw firmly in place and clamped to the sole of the shoe but also forms a reinforcement for the projecting portion of the screw stud, and by externally screwthreading this 45 reinforcing sleeve 11, the metal core of the cleat may be readily screwed thereon and the member 10 then forms a stud of large diameter for the detachable engagement of the cleat therewith.

It has been found that where cleats of this 50 character are secured in place by means of a single screwthreaded stud or bolt that this stud is very liable to be broken off at the base of the cleat under the heavy strains to which the cleat is subjected, the stud being 55 weakened at this point by its external screw thread, but in the present construction the sleeve 11 forms the stud upon which the cleat is mounted and as this sleeve is provided with a base flange in firm contact with the 60 outer surface of the shoe sole, it forms a very strong and rigid reinforcement for the screw stud and as the metal core or thimble of the cleat is screwed upon the sleeve 11 into firm contact with the flange 12, there is 65 no chance for play or lateral movement of

the cleat which would put a heavy strain upon the comparatively small screw stud 7 and tend to break it off.

In the ordinary construction, when one of these screw studs breaks off within the 70 cleat, it is very difficult to remove the broken portion of the stud from the cleat and it is therefore necessary to throw the cleat away and provide a new one and also to remove the portion of the stud from the shoe sole 75 and put another in its place. In the present construction, the removal of the cleat when it becomes worn is an easy matter because of the clamping member 10 being screwed into the socket or thimble of the cleat with 80 this thimble entirely closed to exclude the dirt and dampness and with the thimble seated upon the flange of the clamping member. When the body of the cleat becomes 85 worn away in use, it is therefore a simple matter to unscrew it from the sleeve 11 and screw another in place thereon. Further the core or thimble which is embedded within 90 the body of the cleat 4 is of sufficient diameter to afford a very strong and rigid reinforcement for the body of the cleat and therefore the liability of the cleat body becoming broken away in use and exposing 95 the metal core is obviated and should the body become worn away in use, the comparatively smooth and rounded outer end of the core only will be exposed and injury to other players will be reduced to the minimum.

To provide a firmer and more rigid base 100 or place of attachment for the screw stud to the shoe sole, it may be found desirable, particularly in the more expensive shoes, to insert between the insole 2 and the outer sole 1 a thin sheet metal sole plate 16 having 105 elongated openings 17 therein placed in the positions in which it is desired to attach the several cleats 4. When such a sole plate is used, the screw stud 18 is inserted through one of the openings 17 and through a suitable hole provided in the outer sole of the shoe, with the head 19 of the stud in contact with the inner surface of the plate and beneath the insole 2. The stud 18, directly 110 beneath the head 19 is formed with an elongated neck portion to fit within the elongated opening 17 in the plate 16 and thus prevent rotation of the stud, and adjacent this portion 20 is an annular groove 21 formed 115 in the neck portion of the stud between the elongated portion 20 and a conical portion 22. After the stud has been inserted in the opening in the sole plate, a collar or ring 23 which is of a very close fit over the portion 22 of the neck of the stud and this collar 120 is forced on to the neck and over the groove 21 so that it will spring into the groove 125 slightly and thus the stud will be firmly clamped in place within the opening in the sole plate.

In the construction where a sole plate is used, the stud 18 may and preferably is of a larger diameter at its screw-threaded outer end, and as it is very firmly and rigidly supported by the sole plate, it becomes unnecessary to reinforce the outer screwthreaded end of this stud by means of a reinforcing member and therefore the outer end of the stud is screwed directly into the core or 10 thimble 5 of the cleat 4.

Obviously other changes in the construction and arrangement of parts may be made within the scope of the appended claims without departing from the spirit of the invention and I do not limit myself to the particular construction shown.

Having thus fully described my invention what I claim is:

1. In combination with a shoe having a sole portion provided with an opening therethrough, a screwthreaded stud to project through the opening and having a head to engage the inner part of the shoe sole, a tubular reinforcing member having an internal screw thread to engage the outer end of the screw stud and firmly clamp the sole portion of the shoe between said head and reinforcing member, means for preventing rotation of said stud within the shoe sole and a cleat screwed upon the outwardly projecting tubular reinforcing member.

2. In a shoe having a sole portion provided with an opening, a screwthreaded stud extending through said opening and having a head on its inner end, a tubular reinforcing member having an outwardly extending flange at one end and screwed upon the outer end of said stud to firmly clamp the sole portion of the shoe between the head on the stud and the flange on the reinforcing member, means for securing the reinforcing member to the shoe sole to prevent rotation of the reinforcing member on the stud, and a cleat detachably engaged with the outwardly projecting portion of the reinforcing member and having a recess in its base to receive the flange on the reinforcing member.

3. The combination with a shoe having a sole portion provided with an opening, of a cleat comprising a body and a hollow metal core extending within said body from the base thereof and internally screwthreaded, a screwthreaded stud extending through the opening in the shoe sole, a reinforcing tubular member internally screwthreaded to engage the outer end portion of the stud and externally screwthreaded to screw into said core.

60 In testimony whereof I affix my signature.
ALBERT E. SHEILL.
